UNITED STATES PATENT OFFICE.

ROWLAND CHARLES JORDAN, OF WINNIPEG, MANITOBA, CANADA.

CLOTHES-CLIP.

1,285,724.

Specification of Letters Patent. Patented Nov. 26, 1918.

Application filed September 27, 1916. Serial No. 122,498.

To all whom it may concern:

Be it known that I, ROWLAND CHARLES JORDAN, of the city of Winnipeg, in the Province of Manitoba, Dominion of Canada, have invented certain new and useful Improvements in Clothes-Clips, of which the following is the specification.

The invention relates to improvements in clothes clips of that class which are best known as clothes pins and the object of the invention is to provide a sanitary, durable, inexpensive and efficient clip which will effectively hold clothes on a clothes line and which can be readily released from the line to remove the clothes.

A further object is to provide a clip which will not have any tendency to tear the clothes when being applied or removed or when in use and also one which will not readily freeze to the clothes and one also which can be easily washed and kept clean.

With the above objects in view the invention consists essentially in a clip formed from a single strand of wire bent to provide two spring loops and a retaining fastener for the ends of the wire, the parts being arranged and constructed as hereinabove more particularly described and later pointed out in the appended claims reference being had to the accompanying drawings in which:—

Figure 1 represents a perspective view of the clip.

Fig. 2 represents a front view of the clip shown in Fig. 1.

Fig. 3 represents a pair of clips as they appear when holding the clothes on the line.

Fig. 4 represents an enlarged detailed vertical sectional view through the retaining fastener applied on the loops.

Fig. 5 represents a vertical sectional view through the loops, the section being taken in the plane denoted by the line X—X' Fig. 2.

In the drawing like characters of reference indicate corresponding parts in the several figures.

The clip comprises a single strand of wire 1 bent to present two more or less similar loops 2 and 3 and having the ends of the wire held by applying a fastening 4. The loops have the upper and lower portions thereof somewhat flattened, the flattened parts being connected by upwardly

converging, slightly bowed, side arms 5, 6, 7 and 8 and the ends 9 and 10 of the wire forming the loops are positioned beneath the common cross strand 11 connecting the loops where they are fastened to the strand by means of the fastener 4 in the nature of an enveloping band.

The band is a split metallic one and it is applied to hold the ends of the wire in position beneath the top strand 11.

From observing Figs. 1 and 2 it will be obvious that if the band be tightly applied on the ends of the wire forming the loops, they cannot pull out as they are shouldered against the outlying portions of the clip wire.

In the finished clip the lower portions of the loops are spread apart as best shown in Fig. 5 so that they will conveniently straddle a clothes line.

Further the loops are offset laterally, one in respect to the other as best shown in Fig. 2 to give an increased spread and also to permit of the easy application of the clip on the line.

After these clips are made I consider it desirable to coat them, such as by dipping, with enamel or porcelain. This coating is indicated by the reference numeral 12. By so coating the clips I make them more sanitary and give them a more pleasing appearance and avoid the possibility of them freezing to the clothes as very often occurs with other forms of clips.

In using the clips the clothes as indicated at 13 are suspended from the line 14 by folding over the line in the customary way. One or more of my clips are then straddled over the line on the folded clothes, one of the loops passing to the front and one to the back. As the loops are formed from spring wire and the fastening holds them more or less tightly together they resist spreading and consequently effect the jamming and clipping of the clothes on the line.

What I claim as my invention is:—

1. A clothes clip consisting of a single strip of wire bent to provide two loops connected at the top by a single cross strand and having the ends of the wire bent to lie beneath and terminating under the cross strand and a metallic sleeve enveloping the cross strand and underlying ends of the wire and holding them together.

2. A clothes clip consisting of a single

strip of wire bent to provide two offset ends of the wire and with the ends thereof loops connected at the top by a single cross extending to the sides of the loops. 10 strand and having the ends of the wire bent to lie beneath and terminating under the strand and with the loops each presenting arcuate gripping ends terminating in converging sides and a metallic fastening sleeve enveloping the cross strand and underlying

Signed at Winnipeg, this 30 day of August 1916.

ROWLAND CHARLES JORDAN.

In the presence of—

G. S. ROXBURGH,
ROLAND FOSTER.
